HORSESHOE

Otto Swanstrom, Duluth, Minn.

Application May 13, 1935, Serial No. 21,145

6 Claims. (Cl. 168—13)

My invention has for its object the provision of a resilient horseshoe of rubber or other suitable material in which is embedded a horseshoe shaped metal reinforcing plate having striking lugs extending outwardly through the body to facilitate the bending of the reinforcing plate to adjust the heel portions of the shoe toward or from each other to fit different shaped hoofs.

Other objects of the invention will hereinafter appear in the following specification.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a bottom plan view of the improved horseshoe;

Fig. 2 is a top plan view of the same with some parts broken away and sectioned;

Fig. 3 is a side elevation of the improved horseshoe with some parts broken away and sectioned;

Fig. 4 is a front elevation of the improved horseshoe; and

Figs. 5, 6, 7, 8 and 9 are detail views in section taken on the lines 5—5, 6—6, 7—7, 8—8, and 9—9 of Fig. 2.

The improved horseshoe includes a resilient body 10, preferably of rubber, but may be of any other suitable resilient material, and a horseshoe shaped metal reinforcing plate 11 embedded in said body or, in other words, the body 10 is molded around the reinforcing plate 11. This reinforcing plate 11 is relatively thin, in respect to the thickness of the body 10, is of substantially a constant width, and is positioned in the body 10 close to the upper surface thereof so that there is only a relatively thin thickness of rubber on the upper face of said plate.

Formed with the toe portion of the reinforcing plate 11 is a plurality of relatively large holes 12 and in each end portion of said plate is a like hole 13. The holes 12 are, as shown, five in number and one thereof is directly back of the upstanding clip 14 on the toe of the reinforcing plate 11 and two on each side thereof. These holes 12 and 13 are filled with rubber at the time the body 10 is molded and said rubber forms a bond between the sections of the rubber above and below the reinforcing plate 11 and also materially assist in holding said plate against strain to shift edgewise in the body 10. The clip 14 is also faced with rubber within which it is molded.

Formed in each wing of the body 10 and the reinforcing plate 11 is a series of nail holes 15. The sections of the nail holes 15 in the body 10 extend inwardly from each face of said body and terminate short of the faces of the reinforcing plate 11. During the molding of the body 10 around the reinforcing plate 11 the nail holes in said plate are filled with rubber and it will thus be seen that the metal reinforcing plate 11, at the nail holes 15, is covered with rubber and thereby protected from rust up to the time the shoe is placed on a horse's hoof and at which time nails are driven through the rubber filling the intermediate portions of the nail holes 15.

The sections of the nail holes 15 in the tread 15 side of the body 10 are shaped to receive the heads of the nails, not shown. Each wing of the body 10 is recessed at the respective series of nail holes 15, as indicated at 16, to materially reduce the thickness of the body 10 under the reinforcing 20 plate 11 and surrounding the nail holes 15. The tread face of the body 10 is flat and continuous from the toe to the heel of each wing and the thickness of the body 10 below the reinforcing 25 plate 11 is progressively decreased from the heel of each wing to the toe to tilt the hoof-engaging surface of the body 10 and give the same the proper pitch.

Formed with the inner edge of each wing of the reinforcing plate 11 is a striking lug 17 and 30 a like lug 18 is formed with the outer edge of the respective wing. These striking lugs 17 and 18 are located on the heel portion of the reinforcing plate 11 with the lugs 18 rearwardly of the lugs 17, see Fig. 2. Said lugs 17 and 18 extend outwardly through the body 10 and their outer ends are exposed and flush with the respective surfaces of the body 10.

The purpose of the lugs 17 and 18, which is the primary object of this invention, is to afford 40 striking surfaces which may be struck with a hammer or otherwise to cold bend the reinforcing plate 11 and adjust the heel portions thereof toward or from each other to fit the body 10 to a hoof. To facilitate the bending of the reinforcing 45 plate 11 each of its wings is weakened on the respective side of the toe of the shoe by forming in the outer edge of the respective wing a long notch 19. Back of each notch 19 are two of the holes 12 which facilitate the bending of the reinforcing 50 plate 11 at the respective point. Obviously, the notches 19 determine the bending points of the reinforcing plate 11.

The lugs 17 and 18 afford rigid contact points 55 for the jaws of a vice or an anvil when bending

the reinforcing plate 11, if found necessary to use the same.

By reference to Figs. 1 and 9 it will be noted that the curve of the toe portion of the body 10 is flattened to increase the thickness of the wearing surface of the body 10 between the recesses 16 and on each side of the toe, as indicated at 20. This wearing surface extends substantially straight from the tread surface of the body 10 to the tops of the recesses 16 and from there are tapered to the hoof-engaging surface of the body 10.

The drawings illustrate a commercial form of the invention, but it will be understood that the same is capable of certain modifications as to details of construction, arrangement and combination of parts within the scope of the invention herein disclosed.

What I claim is:

- 20 1. A horseshoe, the body of which is formed from resilient material, a horseshoe shaped metal reinforcing plate embedded in the body, and striking lugs on at least one of the edges of the reinforcing plate at the heel portions thereof and extending outwardly through the body, the ends of the striking lugs being substantially flush with the respective surfaces of the body.
- 25 2. A horseshoe, the body of which is formed from resilient material, a horseshoe-shaped metal reinforcing plate embedded in the body, and striking lugs on the inner and outer edges of the reinforcing plate at the heel portions thereof and extending outwardly through the body, the ends of the striking lugs being substantially flush with the respective surfaces of the body.
- 30 3. The structure defined in claim 2 in which the striking lugs on each heel portion of the re-

inforcing plate are positioned, the one in advance of the other.

4. The structure defined in claim 1 in which the reinforcing plate at its outer edge portion on each side of its toe is provided with a long 5 notch to define the bending point of the respective wing of the reinforcing plate in adjusting its heel portion toward or from the other wing of said plate, said reinforcing plate having transverse holes inwardly of its notches through which 10 the body material extends.

5. A horseshoe, the body of which is formed from resilient material, and a horseshoe shaped metal reinforcing plate embedded in said body, said plate being relatively thin in respect to the 15 thickness of the body and with its upper face close to the upper face of the body, each wing of the body and the reinforcing plate having a series of nail holes, the body at each series of nail holes being recessed to reduce the thickness of 20 the body material under the reinforcing plate, the tread of the body being substantially flat and continuous from the toe to the heel of each wing, the curve of the outer surface of the toe portion of the body between the recesses being flattened 25 to progressively increase the transverse thickness of the wearing surface of the body on each side of the toe.

6. A horseshoe, the body of which is formed from a resilient material, a horseshoe-shaped 30 metal reinforcing plate secured to said body with its edges covered thereby, and striking lugs on said edges extending outwardly through the body with their ends substantially flush with the respective surfaces of the body. 35

OTTO SWANSTROM.
